UNITED STATES PATENT OFFICE.

THOMAS A. SMITH, OF SALEM, INDIANA.

COFFIN AND CASKET LID.

No. 820,744.

Specification of Letters Patent.

Patented May 15, 1906.

Application filed July 10, 1905. Serial No. 268,995.

To all whom it may concern:

Be it known that I, THOMAS A. SMITH, a citizen of the United States, residing at Salem, in the county of Washington and State of Indiana, have invented certain new and useful Improvements in Coffin and Casket Lids, of which the following is a specification.

This invention relates to coffins and caskets, and pertains especially to the class of lids or tops for the same. While the invention may be employed on coffin tops or lids of various character, it is specially designed as an improvement upon my canopy-top casket patented December 16, 1902, No. 716,122.

15 It is obvious that ordinarily to entirely expose the contents of a coffin or casket the top or cover must be entirely removed therefrom, that in the case of my canopy-top casket only part of the interior is exposed when said top 20 is raised, that when said top is closed it is incapable of being slid to expose any part of the interior of the coffin, and that the majority of caskets have doors or slides movable lengthwise the casket only sufficient to expose a 25 portion of the contents of the casket, or the whole top is slideable lengthwise the casket, which only reveals a portion of the contents of the coffin or casket. It is therefore the purpose of this invention to provide means 30 whereby the whole body of a corpse may be disclosed to view in a canopy-top casket without removing said top but partly from the casket.

The invention consists in means for connecting a lid or top to a coffin or casket so as 35 to be slid across the latter to disclose the whole length of a corpse.

The invention further consists in a novel connection between a casket and its canopy-top whereby the latter may be slid part way 40 across the casket to disclose to view the entire contents of the casket.

Various other advantages are attained by the details of construction and arrangement 45 of parts, resulting in simplicity and expeditious operation of casket-lids.

In the accompanying drawings, forming part of this application, Figure 1 is a perspective view of a canopy-top casket embodying 50 my invention shown in open position. Fig. 2 is a side elevation showing the casket closed. Fig. 3 is a longitudinal section on the casket in closed position. Fig. 4 is a detail cross-section on the line $z z$, Fig. 2, showing 55 the movable position of top in dotted lines. Fig. 5 is a perspective view of one end of a

casket, showing a modification. Fig. 6 is a detail section on the line $y y$, Fig. 5. Fig. 7 is a top view of a casket partly open, showing a further modification. Fig. 8 is a detail section on the line $z z$, Fig. 7, partly broken away.

The same reference-numerals denote the same parts throughout the several views of the drawings.

60 The invention as preferably used will be shown and described in connection with a casket having a canopy-top such as covered by my aforesaid patent, which has a drop side carrying with it part of the front top molding.

65 The improvements hereinafter disclosed provide for the shifting of the top molding or frame whether the lid is open or closed and for dropping the whole of the front top molding without dropping the side of the casket.

70 The lid portions 1 and 2 are hinged together, and the portion 1 is hinged to the top molding or frame 3. The lid portion 1 has one end of a lever 5 pivoted thereto, the other end of the lever 5 being slideable on a rod 6, 75 secured to the lid portion 2, and a prop 7 is pivoted to the frame 3 for holding the lid in raised or canopy position.

75 The frame 3 is independent of the casket, and the front portion 8 of the frame is separate from the latter and is carried by the drop side 9 of the casket. A pair of links 10 are pivoted at 11 in each end 12 of the casket and incline upwardly above the casket edge and are pivoted at 13 in the ends of the frame 3.

80 In shifting the frame across the casket the links give it a slight pivot or swinging movement, which is stopped in either direction by the frame ends striking the top edge of the casket ends. It is obvious that by this arrangement the entire length and breadth of the contents of the casket may be disclosed and that the lid may be opened and closed with the lid-frame in either position.

85 Referring to the modification shown in Figs. 5 and 6, one side 14 of the lid-molding is hinged to the top edge of the casket, and the ends of the latter are provided with an angle-plate 15, secured upon the inner side of said 90 ends and overlapping the top of said ends. This overlapping portion has a slot 16, in which a screw 17 is adapted to slide, with the screw-head working in a groove 18, formed in the top edge of the casket ends. By this arrangement no part of the device is visible 95 when the lid is closed, and the latter is slid

only about a third of the length of the casket ends to disclose the whole form of a corpse.

Referring to the modification shown in Figs. 7 and 8, the under side of the molding or lid-frame is provided at its ends with a plate-disk 19, set into the molding by suitable screws, and said plate has a cam-face around a central hole 20. The casket ends have a track 22, secured therein by screws 21. A track 22 has beveled sides or is dovetailed in cross-section, and said sides have flanges 23, spaced by a slot 24, which flanges overhang the base of the track, so as to leave an interval or space 25 throughout the length of the track. A slideable screw-stud 26 extends through the lid-molding at each end, and the studs are provided with a bushing 27 and a hand-knob 28. Both of the studs being of the same construction, only one of them will be described in detail. The screw portion of the stud extends through the bushing 27 to receive a knob 28, having its bearing on the bushing. The stud has a rectangular head 29, adapted to be inserted through the slot 24 into the space 25 of the track, and a circular bearing 30 is formed between the stud-stem and its head to fit the said slot, and on the top face of the bearing 30 is formed a cam 31, adapted to coöperate with the disk-cam in locking the lid to the casket.

The tracks are placed in position by inserting them endwise into the ends of the casket before the sides of the casket are positioned, and it is only necessary to have the tracks extend part way the length of the casket ends. It is obvious that after securing the tracks in place the plate-disks are placed in position to aline the plate-hole and the track-slot, so that the stud may be slid in the track as desired.

I do not wish to be understood as limiting myself in the application of these improvements to canopy-caskets or to drop-side

caskets, nor do I confine myself to any number of links employed.

Having thus described my invention, what I claim as new, and desire to secure by Letters Patent, is—

1. The combination, with a coffin or casket, of a lid-frame, and the links pivoted in pairs at one end to the lid-frame ends and having the other end pivoted to the coffin ends on each side of the center of the coffin ends for supporting said frame.

2. The combination, with a coffin or casket, of a lid-frame having one of its sides hinged to the coffin, a pair of links at each end of the frame and connecting these ends with the coffin ends to permit the lid to be swung across the coffin independent of said frame side to open and close the coffin.

3. The combination, with a coffin or casket, of a lid-frame having its ends and one side connected and movable together, the other side being separate and movable independently, and means connecting the frame with the coffin to effect said movements.

4. The combination, with a coffin or casket, of a lid-frame movable across the casket, a canopy-lid movable with the frame and adapted to be adjusted thereon independent of the frame movement, and means connecting said frame with the casket.

5. The combination, with a coffin or casket, of a lid-frame movable across the casket, a canopy-lid hinged to the frame and adapted to be adjusted independent of the frame movement, and a pair of links pivoted in each end of the casket and having separate pivot connections with the ends of the frame.

In witness whereof I hereunto set my hand in the presence of two witnesses.

THOMAS A. SMITH.
